METHOD AND APPARATUS FOR HEATING
BILLETS

Sam F. Keener, Salem, Ohio

Application May 20, 1939, Serial No. 274,760

10 Claims. (Cl. 266—5)

This invention relates to an improved method and apparatus for heating metal billets and more particularly to the uniform heating of such billets customarily employed in the production of seamless tubes preparatory to the piercing operation of the process producing the tubes. The invention, by reason of the utilization of the improved billet heating method and apparatus of the invention, also relates to an improved relative arrangement or lay-out of the various equipment required in the production of the tubes, which arrangement effects definite economies, to be hereinafter pointed out, in the production of the tubes.

Heretofore, the apparatus employed for the purpose of uniformly heating metal billets and more specifically the heating of such billets preparatory to the piercing operation aforesaid embraced a heating furnace of the inclined hearth type in which the billets are manually rolled down, a heating furnace of the walking beam type in which suitable mechanical contrivances are employed to propel the billets through the furnace, and a billet heating furnace of the batch type in which the billets are simply deposited on suitable fixed supporting surfaces and manually periodically moved to effect uniform heating of them. Considerable manual labor is required in the operation of furnaces of the first and last mentioned types, as the billets must be handled manually and in furnaces of the sloping hearth type a multiplicity of doors must be provided along the side walls thereof to afford access to the billets as they proceed along the hearth. In addition, the charging opening at the upper end of the furnace and the discharging opening at the lower end of the furnace, together with the inclined nature of the furnace, create a stack effect therein and this, together with the openings in the side walls of the furnace, makes the maintenance of proper heat distribution within the furnace a very difficult matter. In operation, furnaces of this character allow large volumes of hot gases to rise out of the upper portions of the furnaces and admit correspondingly large volumes of cold air in the lower portions, which tends to result in a cool discharge hearth requiring closing of the furnaces and interruption of the production process. Also, the introduction of large volumes of fresh air renders the maintenance of the advantageous reducing atmosphere within the furnace impossible, causing scaling of the billets. By reason of the substantial hot gas losses considerable fuel, in excess of that required to heat the billets and furnace, is required.

Characteristic of the operation of the walking beam type of furnace is the streaking of the billets due to the portions thereof which are immediately adjacent the supporting and propelling beams being cooled, the beams being water cooled in accordance with usual practice. The non-uniformity of heating resulting from the streaking renders the billets unsuitable for working and, therefore, in such furnaces a second stationary hearth is provided at the discharge end of the beams on which the billets may be supported for a short interval of time to insure elimination of the streaks before they are transferred to the piercing mill or other working apparatus. The uniform heating of the streaked billets on such secondary hearth requires some manual manipulation and sound judgment on the part of the operator tending such billets. The apparatus utilized in a furnace of the walking beam type requires considerable maintenance and, since it is difficult to seal the special hearth employed because of the mechanical supporting and moving members therefor, it is difficult to control the pressure and atmosphere within the furnace. Also, since the secondary hearth is sloped to facilitate manipulation of the streaked billets, a stack effect, similar to but less in extent than that described above in connection with the roll down furnace, is attained.

The batch type of furnace which is used to a lesser extent than the other types specifically mentioned above has, as its principal operating disadvantage, the requirement of considerable skilled manual labor and limitations of plant layout since the billets must all be continuously moved to insure their uniform heating and therefore sufficient usable space provided to accommodate the operators. Inasmuch as a plurality of discharge points must be provided for a furnace or furnaces of the batch type to supply heated billets to a piercing mill, the distance between such points and the mill will vary and the temperature of the hot steel brought to the mill will vary accordingly due to the heat loss of the individual pieces during travel from the points of discharge to the mill. A satisfactory uniform production is difficult to attain under such conditions, the rate of production of the mill is reduced and consequently highly efficient operation of the plant can not be maintained.

The primary objects of the invention are the provision of an improved method and apparatus for heating the billets preparatory to the piercing operation and the provision of an improved arrangement of such apparatus relative to the other essential equipment of the plant whereby

a higher rate of production may be maintained, a more uniform product produced, and less labor required for such production. These objects are accomplished, according to my invention, by employing a circular furnace having a rotary hearth therein and having a discharge point adjacent to the piercing mill and a charging point adjacent to the discharge point. For reasons to be hereinafter specifically set out, the employment of a furnace of this type for the purpose and in the relative position indicated results in a more uniform and economical heating of the billets, reduces the handling of the same into and out of the heating furnace and enables the furnace charging and discharging apparatus to be more closely grouped whereby better control may be exercised over the operation of the plant.

A more specific object of the invention is the provision of an improved furnace for heating metal billets preparatory to their working in a piercing mill and of an improved arrangement for charging the billets into the furnace and withdrawing the same therefrom whereby definite economies are effected in the operation of the billet handling and heating phases of the tube production process.

Another object of the invention is the provision of an improved arrangement of apparatus for handling and heating billets preparatory to their working in a piercing mill whereby the billets will be uniformly heated and will reach the piercing mill at a uniform temperature with a minimum of apparatus required for the handling and heating. Yet another object of the invention is the provision of apparatus for the purposes stated which is operable with a minimum of labor, which reduces the formation of scale on the billets, and which is rugged in service.

These and other objects and advantages of the invention will become apparent from a consideration of the accompanying drawings and the following detailed specification wherein there is specifically disclosed a billet heating furnace constructed in accordance with my invention and a lay-out for a portion of a plant for the production of seamless tubes.

In the drawings:

Figure 1 is a plan view of a portion of a plant for the production of seamless tubes arranged according to my invention, a portion of the billet heating furnace being shown in section to illustrate the manner in which the billets are charged into the furnace and carried therein;

Figure 2 is a vertical section through the apparatus of Figure 1, said section being taken along the line II—II of Figure 1; and

Figure 3 is a fragmentary section along the line III—III of Figure 1.

Referring now to Figure 1 of the drawings, which diagrammatically illustrates that portion of a seamless tube production plant with which the present invention is concerned, reference numeral 10 indicates generally a continuous billet heating furnace and reference numeral 11 indicates a piercing mill for performing the first working operation on the billets in the tube production process. Furnace 10 is circular in plan—having a cylindrical inner side wall 12, a similar outer side wall 13, and an annularly-shaped roof 14 spanning the concentric side walls. Positioned within the furnace between the side walls 12 and 13 is the annular hearth 15 suitably supported for rotative movement about its own center which center is coincident with the centers of the walls

12 and 13. Adjacent openings 16 and 17 are provided in the outer furnace wall 13 to allow passage of the billets into and out of the furnace, respectively.

Extending outwardly from each of the openings 16 and 17 is a framework 22 adapted to movably support a material handling machine 21 commonly termed a charging machine. In accordance with usual practice, the machine 21 may consist of a carriage for the support of the drive and control equipment and the operator, and a water cooled peel 23 carried by and extending outwardly from the carriage. As is well understood, the peel 23 is mounted for considerable manipulative movement and as employed in the apparatus of this invention is provided at its outer end with a pair of tongs 24 which may be clamped about the billets being handled to deposit the same within or withdraw the same from the furnace as the case may be.

Associated with the charging machine 21 adjacent the inlet door 16 of the furnace is a transfer table 19 onto which cold billets may be placed and moved beneath the tongs of the machine preparatory to their being charged into the furnace. A transfer table 20 is associated with the charging machine adjacent the discharge opening 17 of the furnace to receive the heated billets as they are withdrawn from the furnace by the machine. Table 20 abuts against a conveyor 26 which is operative to quickly move the heated billets to the vicinity of the piercing mill or mills 11 of the plant. For efficient handling of the material the axis of the mill 11 is preferably parallel with the general longitudinal axis of the conveyor 26, a transfer table 27 being employed to move the heated billets from conveyor 26 to mill 11. Piercing mill 11 is preferably placed on the same side of the conveyor 26 as the furnace charging machines and in the event that two such mills are to be employed in combination with the furnace, they may be positioned on either side of the conveyor as illustrated in Figure 1—an additional transfer table 28 being employed to move the heated billets to the second mill.

Referring now more particularly to Figure 2 of the drawings, the billet heating furnace 10 is built up between two concentric series of buckstays 31 the functions of which are to provide lateral and vertical support for the side walls 12 and 13 and support for the gas, air and flue ducts to be later described. A circular channel 32 is secured to the inner surface of the outer ring of members 31 adjacent the lower ends thereof and this, together with a multiplicity of circularly arranged members 33, supports the side walls of the furnace. Furnace hearth 15 which may be of solid refractory brick construction as shown or which may be provided with piers for supporting the material in order to provide circulation of gases all around the billets is supported on a suitable structural steel platform 47, the latter being carried by a number of wheels 48—49 (the inner or outer set being flanged as at 48) traveling on the rails circles 50—51. Rails 50—51 are supported on a frame work 52, the latter as well as the entire furnace being supported on a suitable concrete base 30. Suitable mechanism (not shown) is employed to rotate the hearth 15 within the furnace at a controlled rate of speed and to start and stop such rotation.

Evenly spaced about the entire periphery of both the inner and outer walls 12 and 13, respec-

tively, of the furnace and adjacent the upper ends thereof are the fuel burners 38 indicated schematically for burning gaseous fuels. The latter and the compressed air required for its efficient combustion are conducted to the burners through the circular conduits 39 and 40, respectively, carried adjacent the roof of the furnace and immediately adjacent the ring of buckstays 31 on cross members 34 fastened to the buckstays. Suitable conduits (not shown) connect the individual burners with the tubes 39 and 40. Evenly spaced about the peripheries of the walls 12 and 13 of the furnace and intermediate the burners 38 are the passages 35 which open to the space within the furnace in a horizontal plane substantially as low as or lower than the billet supporting surface of the hearth 15 and which extend upwardly through the tops of the walk to communicate with the tubular manifolds 36 and 37 positioned immediately above the walls 12 and 13, respectively. As indicated in Figure 1, the manifolds 36 and 37 are connected through conduits 64, 68 and a motor driven exhaust unit 65 with a stack 66. Pressure within the furnace may be controlled by operation of the unit 65 but if the stack 66 is of sufficient height, the unit 65 may be dispensed with and the pressure controlled by means of dampers. Also, it should be apparent that recirculating systems and other known arrangements for controlling the pressure within the furnace may be satisfactorily employed in connection with the billet heating furnace of this invention since the furnace is entirely closed except for the small openings 16 and 17 existent when the furnace is being charged and discharged. When the latter operations are not in progress, openings 16 and 17 are closed by the sliding doors 45. Note Figure 2.

Hearth 15 is sealed from below by sand seals which consist of quantities of sand in the circular troughs 54 and 56 carried by members 33 and the cylindrically formed plates 55 and 57, the lower ends of which extend down into the sand carried by troughs 54 and 56, respectively. Plates 55 and 57 are secured to the sides of the hearth 15 and inasmuch as they are circularly concentric with the troughs the seals are effectively maintained even during travel of the hearth. A shoulder is provided at each of the inner and outer edges of the hearth and grooves 60 and 61 are provided on the shoulders to retain scale and other foreign matter dropping from the hearth proper, thereby preventing such material from becoming lodged in the seals or between the sides of the hearth or hearth support and the furnace walls 12 and 13, whereby the proper functioning of the seals and the rotation of the hearth will not be interfered with.

If it is thought necessary or desirable to turn the billets on the hearth as the hearth is rotated there may be provided, in accordance with the present invention, a pivoted bar or other member 70 suspended from the furnace roof 14 (Figure 3) and having a curved lower surface 71 to engage and override the billets 63 as the latter move underneath on the hearth. Member 70 has sufficient mass or, if required, a biasing means is employed, to insure sufficient frictional contact between the surface 71 and the billets 63 to rotate the latter approximately 180° during such contact.

The furnace and its ancillary equipment are arranged relatively to each other and to the piercing mill as indicated in Figure 1 which results in the grouping of the charging machines

21 and other apparatus requiring human operatives. A better control may therefore be exercised over the functioning of the plant and the number of employees required for manning the plant 5 may be reduced. In operation, with the furnace previously heated, cold billets deposited on table 19 are picked up by the adjacent charging machine 21 and moved radially inward through the opening 16 and deposited in a radial position on the hearth 15. The charging continues as the hearth revolves and when the billets reach the opening 17 after having traversed substantially the entire length of the furnace, they will be 10 engaged by the tongs 24 of the machine 21 used 15 for unloading, withdrawing from the furnace, and deposited on the table 20 from whence they will pass to the piercing mill. During normal operation of the plant, the charging, heating, and discharging of the billets continues uninterrupted and by reason of the space efficiency of 20 the rotary furnace, the billet heating capacity of the plant will be adequate for all plant requirement.

It should be observed that by reason of the 25 manner in which the billets are charged into and withdrawn from the furnace, i. e., longitudinally, the size of the openings required in the side wall of the furnace for their passage is very 30 small and consequently the temperature, pressure and character of the atmosphere within the furnace is more easily maintained. Unnecessary heat losses are reduced to a minimum and the degree of scaling caused by contact of fresh air with the heated billets is also minimized. In addition, this method of handling the billets 35 utilizes more efficiently the space on the hearth within the furnace and enables a relatively simple arrangement, as shown in Figure 3, to be employed to automatically turn the billets, if required, during their travel through the furnace.

40 For reasons pointed out above and for the additional reasons that the billets are constantly moved under the flames and that a much better distribution of heat is obtained within the furnace, a more satisfactory heating of the billets 45 can be effected. In this furnace the gases are caused to swirl entirely around the furnace and to move downwardly to the hearth and outwardly therealong to the inlets to the ducts 35 50 all of which results in a more uniform distribution of heat within the furnace and more rapid heating of the billets. Such heating is accomplished without streaking the billets and without any manual manipulation of the same.

55 The present invention provides a method and apparatus for heating billets in which the heating is thoroughly and economically accomplished substantially automatically—the only labor required being the two operators required for operating the machines 21 and an engineer in charge of the operation of the furnace. The uniformly heated billets all leave the furnace through the opening 17 and the length of travel of all the billets from the furnace to the piercing mill is the same resulting in uniformly heated billets reaching the piercing mill and consequently a higher rate of production of such mill. The path of travel of the billets from the furnace to the mill is short and direct requiring a minimum of handling for the billets and in this connection it is pointed out that if space arrangements permitted the conveyor 26 could be placed directly under the discharging machine 21 and in alignment therewith thus dispensing with the transfer table 20.

It should now be apparent that I have provided an improved method of heating and handling metal billets preparatory to their utilization in tube manufacturing and other processes and that such method is capable of being carried out by such apparatus in an expeditious and economical manner. It should also be apparent that the use of the method and apparatus results in a more efficient plant layout and a higher rate of production of the plant.

The above specifically described embodiments of the invention should be considered as illustrative only as obviously many changes may be made therein without departing from the spirit or scope of the invention, the extent of which is indicated in the appended claims.

What I claim is:

1. In apparatus for making seamless tubes, the combination with a piercing mill of means to uniformly heat the cylindrical billets preparatory to their utilization in the mill, comprising a heating furnace having inner and outer concentric cylindrical walls, a continuous rotary hearth positioned between said walls and adapted to rotate within the furnace, openings in said outer wall for the passage of billets into and out of said furnace, a charging machine adjacent said furnace opposite each of said openings, said machines being operative to move said billets longitudinally into and out of said furnace, a conveyor for moving the heated billets from the furnace to the vicinity of the piercing mill, the billet entering end of said conveyor being adjacent the machine opposite the billet discharging opening of said furnace.

2. In apparatus for making seamless tubes, the combination with a piercing mill of means to uniformly heat the cylindrical billets preparatory to their utilization in the mill, comprising a heating furnace having inner and outer concentric cylindrical walls, a continuous rotary hearth positioned between said walls and adapted to rotate within the furnace, openings in said outer wall for the passage of billets into and out of said furnace, a conveyor for longitudinally moving the heated billets from the furnace outlet to the vicinity of said mill, said conveyor extending outwardly from the furnace.

3. In apparatus for making seamless tubes, the combination with a piercing mill of means to uniformly heat the cylindrical billets preparatory to their utilization in the mill comprising a heating furnace having inner and outer concentric cylindrical walls, a continuous rotary hearth positioned between said walls and adapted to rotate within the furnace, adjacent openings in said outer wall for the passage of billets into and out of said furnace, adjacent charging machines opposite said openings and adapted to move cold billets through one of said openings onto said hearth and to move heated billets from said hearth through the other of said openings, a baffle wall within said furnace between said openings, and means to move the billets from one of said machines to said mill.

4. In apparatus for making seamless tubes, the combination with a piercing mill of means to uniformly heat the cylindrical billets preparatory to their utilization in the mill comprising a heating furnace having inner and outer concentric cylindrical walls, a continuous rotary hearth positioned between said walls and adapted to rotate within the furnace, openings in said outer wall on the side of said furnace adjacent said piercing mill for the passage of billets into and

out of said furnace, means to charge cold billets through one of said openings and onto said hearth, means to withdraw heated billets from said hearth through the other of said openings and means to transfer heated billets from said last mentioned opening to said piercing mill.

5. In apparatus for making seamless tubes, the combination with a piercing mill of means to uniformly heat the cylindrical billets preparatory to their utilization in the mill comprising a heating furnace having inner and outer concentric cylindrical walls, continuous rotary hearth positioned between said walls and adapted to rotate within the furnace, openings in said outer wall on the side of said furnace adjacent said mill for the passage of billets into and out of said furnace, and conveyor means for moving the heated billets from said furnace to said mill.

6. In apparatus for making seamless tubes, the combination with a piercing mill of means to uniformly heat the cylindrical billets preparatory to their utilization in the mill comprising a heating furnace having inner and outer concentric cylindrical walls, a continuous rotary hearth positioned between said walls and adapted to rotate within the furnace, circumferentially spaced openings in the outer furnace wall for the passage of billets into and out of said furnace, a baffle wall within said furnace between said openings, the opening for the passage of billets out of said furnace being located on the side of said furnace adjacent said mill.

7. In apparatus for making seamless tubes, the combination with a piercing mill of means to uniformly heat the cylindrical billets preparatory to their utilization in the mill comprising a heating furnace having inner and outer concentric cylindrical walls, a continuous rotary hearth positioned between said walls and adapted to rotate within the furnace, openings in the outer wall of said furnace for the longitudinal passage of billets into and out of said furnace, means to move said billets longitudinally into and out of said furnace and to arrange said billets on said hearth, and means to move said billets to said mill.

8. In apparatus for making seamless tubes, the combination with a piercing mill of means to uniformly heat the cylindrical billets preparatory to their utilization in the mill comprising a furnace having concentrically arranged inner and outer walls and a continuous hearth between said walls, means mounting said hearth for rotative movement about the geometric center of said walls, circumferentially spaced openings in the side wall structure of said furnace for the longitudinal passage of the billets into and out of said furnace, means to move the billets through one of said openings and to deposit the same radially on said hearth, means positioned in the path of travel of said billets through the furnace to engage the billets and rotate the same through approximately 180° as they move through the furnace, and means to withdraw the billets through the other of said openings along a line extending radially of the center of said furnace.

9. In apparatus for making seamless tubes the combination with a piercing mill of means to transfer and uniformly heat the solid cylindrical billets preparatory to their utilization in the mill, comprising a heating furnace having inner and outer concentric cylindrical walls, a continuous rotary hearth positioned between said walls and adapted to rotate within the furnace, openings in said outer wall for the passage of billets into

and out of said furnace, a charging machine adjacent said furnace opposite each of said openings and generally aligned with radial lines extending from the center of said furnace through said openings, a transfer table extending at right angles from the charging machine adjacent the charging openings of said furnace, said machines being adjacent to each other and being operative to move said billets longitudinally into and out of said furnace, and a conveyor for moving the 10 heated billets generally endwise from the furnace to the piercing mill.

10. The method of producing seamless tubes

which comprises providing solid metal billets, moving said billets endwise onto a normally continuously moving hearth of a rotary hearth furnace, rotating said hearth at substantially uniform speed and withdrawing the heated billets from the furnace by endwise movement at a point substantially adjacent the furnace charging point whereby the billets will all have reached a uniform desired temperature upon withdrawal from the furnace, moving said billets directly from said furnace to a piercing mill, and piercing said billets.

SAM F. KEENER.
